UNITED STATES PATENT OFFICE.

MARSHALL B. LLOYD, OF MONGMINNEE, MICHIGAN, ASSIGNOR TO HEYWOOD-WAKEFIELD COMPANY, OF BOSTON, MASSACHUSETTS, A CORPORATION OF MASSACHUSETTS.

REED-WEAVING MACHINE.

Application filed August 14, 1925. Serial No. 50,230.

This invention relates to improvements in reed weaving machines and consists of the matters hereinafter described and more particularly pointed out in the appended claims.

5 The invention is herein embodied in machines for weaving a fabric having the characteristics of a reed fabric and one composed of a plurality of spaced members termed "stakes" upon which long strands 10 termed "fillers" are woven over some of the stakes and under others.

The primary object of the present invention is to provide a machine capable of so weaving the fabric as to incorporate therein 15 a design, character or other configuration by laying a plurality of successive courses of filler strands upon the same side of predetermined stakes, thus producing contrasting areas in the fabric, disposed to form the 20 desired design character or configuration therein.

Another object of the invention is to provide a machine of the kind capable of weaving a tubular fabric with designs therein, 25 which machine while simple in construction, is fast and positive in operation.

My invention further consists in the form, construction, arrangement and cooperation of parts whereby the above named objects, 30 together with others which will hereinafter appear are attainable and my invention will be more readily understood by reference to the accompanying drawings which illustrate what I consider at the present time, the 35 best embodiment thereof.

In said drawings:—

Fig. 1 is a view in side elevation of a reed weaving machine embodying my invention.

Fig. 2 is a vertical sectional view on an enlarged scale as taken on the line 2—2 of Fig. 1.

Fig. 3 is a horizontal sectional view on an enlarged scale as taken on the line 3—3 of Fig. 1.

45 Fig. 4 is a vertical detail sectional view on an enlarged scale as taken on the line 4—4 of Fig. 3.

Fig. 4^A is a perspective view of a certain bearing and dog embodied in my improved 50 weaving machine and which will be more fully referred to later.

Fig. 5 is a detail perspective view of parts shown at the mid portion of Fig. 3 and will be more fully referred to later.

55 Fig. 6 is a perspective view of a pattern

controlling plate embodied in my improved weaving machine.

Fig. 7 is a horizontal detail sectional view as taken on the line 7—7 of Fig. 2.

Fig. 8 is a perspective view of a traveller block forming a part of the mechanism shown in Fig. 7.

Fig. 9 is a perspective view of another part of the mechanism shown in Fig. 7.

Fig. 10 is a perspective of a certain combined star wheel and ratchet embodied in my improved weaving machine.

Fig. 11 is a view in elevation of a fragment of a reed fabric produced by my improved machine and illustrates the formation of a diamond shaped design by weaving a plurality of courses of filler strands on the same side of some stakes and on the other side of other stakes.

The machine herein illustrated and described is similar in some respects to the machine shown and described in my prior U. S. Patent No. 1,465,445 issued on Aug. 21, 1923, which machine was incapable of forming designs, characters or other configurations in the finished fabric.

The improved machine comprises generally the following parts or mechanisms, to wit, frame; stake holding and positioning means; stake manipulating means together with pattern plate for controlling the design in the finished fabric; filler strand inserting means and filler strand packing means. As a matter of convenience and in order to simplify and facilitate the understanding of the machine, I shall describe the same in substantially the order above outlined.

The frame.

The frame of the machine comprises a substantially rectangular base plate and arising from each end thereof is a pair of vertically disposed posts 2—2, only one post of each pair being shown herein as in Fig. 1. Said posts are suitably braced from the base by braces 3—3 and the top ends of the posts of each pair are connected together by transverse foot boards 4—4 upon which the operator may stand as when in removing the finished fabric from the machine.

Arising from said base, midway between said pairs of posts, is a suitable standard 5, the top end of which includes oppositely extending parts 6—6. Said standard in-

- cludes vertically aligned bearing sleeves 7-7 in which is journalled a main driven shaft from which the associated mechanisms of the machine receive their motions.
- 5 On the bottom end of said shaft is fixed a large bevel gear 9 which meshes with a pinion 10 on a horizontal drive shaft 11 journalled in the base 1. Said shaft projects at one end beyond one end of the base, 10 and on said shaft end are mounted fast and loose pulleys 12 and 13, respectively. Arranged coaxially with the shaft 8 is a non rotative threaded rod 14, the purpose of which will later appear.
- 15 Fixed to the shaft 8 above the standard 5 is a cylinder 15 having top and bottom flanges. The top flange is formed to provide a complete gear ring 16 and the bottom flange is formed to provide a short gear tooth section 16', as best shown in Figs. 1 and 7, respectively. A suitable end thrust bearing 17 is provided on the top end of the standard 5 for the cylinder 15.
- 20 *Stake holding and positioning means.*
- 25 The stake holding and positioning means includes a circular ring or plate 18 which is fixed to the driven shaft 8 at a point a short distance above the cylinder 15. In 30 the periphery of said ring or plate 18 is formed a rounded groove 19 of a diameter less than that of said ring or plate so as to define top and bottom edge portions in which are formed arcuately spaced notches 35 20-20 of a size to receive the stakes 21. Rising from the top surface of said ring or plate near its periphery is a plurality of vertically disposed relatively short pins 22, one for and in radial alignment with each 40 notch 20. The ring or plate 18 is also provided with diametrically opposite upstanding posts or rods 23-23 of the desired height which extend through suitable openings in a second stake holding ring 24. Said 45 ring 24 removably receives the top ends of the stakes 21 and is formed with a peripheral groove in which is located a yielding stake holding member in the form of a helical coil spring 25. The ring 24 includes 50 a hub 26 and radial arms 27 and associated with said hub is a means for releasably engaging the threaded rod 14 as described in my prior patent hereinbefore referred to. Associated with the groove 19 in the ring 55 or plate 18 is a similar spring 28.

In the starting of the weaving of a fabric the top ring 24 is located quite close to the ring or plate 18 and the top ends of the stakes are inserted in position on said top 60 ring and are held therein by the associated spring 25, with the adjacent portions of said stakes located in the notches 20 of the plate or ring 18 and held therein by the spring 28. With the stakes thus positioned 65 a filler strand 21^a is interwoven or laid over

and under the stakes and by a suitable packing mechanism is packed or moved into substantially close relation to the top ring which serves as a stop against which the filler strand is packed in the first stage of 70 production of the fabric. Thereafter, as the successive courses of filler strands are inserted they are packed against the pre-formed fabric by the means later to be described. 75

Stake manipulating and controlling means.

In the present case a fabric is desired wherein for the major portion thereof the 80 filler strand passes over one stake and under the next adjacent stake and so on and in other portions thereof, a number of strand courses pass over one side of one stake and then under the other side of the next adjacent stakes to present a contrast, the arrangement 85 of the said courses being such as to produce the design, character or other configuration in the finished fabric, as best shown in Fig. 11. To this end I provide a means which is capable of moving each alternate stake out of 90 its normal plane for the passage of the filler strand inserting or laying means and associated with the first mentioned means are devices capable of moving the same stake out of its normal plane a number of times 95 in succession so that a plurality of courses of filler strands are laid upon the same side of said stake.

Secured to the outer end of each standard 100 part 6 is an upright arm 30, the top end of which is formed to provide a sliding guiding bearing for a reciprocating plunger or stake projecting member 31. As shown herein there are two of said plungers located on diametrically opposite sides of the machine but as the mechanism associated with each plunger is the same, a description of one will suffice for both. The inner end of the plunger 31 is normally engaged by a roller 32 carried on the free end of a swingable arm 33 which is pivoted at its opposite end at 34 (see Fig. 8) on a support 35 fixed to the upright arm 30. Said swingable arm has a lateral projection on one side which carries a roller 36 adapted for engagement 105 with the periphery of a toothed-like star wheel 37 rotatively mounted on an upright shaft 38 fixed at its bottom end in the associated standard part 6. 110

The star wheel 37 has a plurality of projections 39 on its periphery and between said projections are shallow recesses 40. On the under side of said star wheel are provided ratchet teeth 41 as best shown in Fig. 10. The star wheel is operatively connected for rotation in one direction with a gear 42 also rotatively mounted on the shaft 38, by means of a spring pressed pawl 43 carried by said gear and which coacts with the ratchet teeth 41 on said star wheel. The 115 120 125 130

gear 42 meshes with the ring gear 16 on the top end of the cylinder 15 and has thrust bearing against a sleeve 38^a in which the top end of the shaft 38 extends, said sleeve being supported by posts 38^b—38^b, upstanding from the standard part 6, as best shown in Figs. 2 and 3. It is apparent that as the cylinder 15 is rotated, the gear 42 is driven thereby and said gear, in turn, through the pawl 43 causes said star wheel to be driven in the same direction. However the driving connection between said gear and star wheel is such that when it is necessary, the star wheel may be rotated or advanced step by step, ahead of the gear for a purpose and in a manner to appear later. As the star wheel is rotated, it will vibrate the arm 33 which, in turn, will reciprocate the plunger 31 and said plunger will engage a stake 21 and project or flex the same out of its associated pocket or recess 20 in the plate or ring 18. This projecting of the stake, is of course in advance of a stake spreader 44 carried on the top end of an upright supporting member 45 upstanding from the base 1 and up through which the filler strand 21^a is conducted to be woven or laid over and under the stakes.

The star wheel is so formed and so timed with reference to the stakes that it will impart a reciprocation to the plunger 31, each time an alternate stake approaches the plane of said plunger which, of course, will project or flex the same outwardly from its normal plane. To insure the return of the projected stake to its proper recess in the ring 18, after it has passed the stake spreader, I provide toothed wheels 46 and 47, one arranged in a plane above and the other in a plane below that of the ring 18. The said wheels are rotatively mounted on a vertical stub shaft 48 located a short distance outwardly from the plane of the stakes and the teeth thereof project through the spaces between the stakes and mesh with the pins 22 in the manner of a gear, the spaces between said teeth receiving the projected stakes. The teeth of the wheel 46 meshing with the pins 22 on the ring 18, as mentioned, are rotatively driven thereby in timed relation with the stakes. The shaft 48 is journaled in the end of an arm 49 adjustably supported by a bolt and slot connection 50 (see Fig. 3) with a cross member 51 that connects two of the standards 2—2 at the associated end of the machine. The construction just above mentioned is fully shown and described in my prior patent hereinbefore referred to so that it is not necessary to go into greater detail regarding the same. This bolt and slot connection however is such that the position of the wheels 46 and 47 may be accurately determined with reference to the position of the stakes. Fixed to the bottom end of the shaft 48 is an arm 52 which includes an offset part 53 arranged in a plane between the wheels 46 and 47, as best shown in Fig. 5. Pivoted at a point between its ends on said offset part is a lever 54 arranged substantially in the plane of the ring 18. The short arm of said lever extends toward the plane of the plunger 31 to be engaged by the projected stakes while the long arm of said lever is connected by a contractile spring 55 with the upturned end of the arm 52. Thus, when each alternate stake is projected by the outward movement of the plunger, it engages the short arm of the lever 54 and moves it outwardly against the action of the associated spring 55, which will return the parts to their normal position after passing the stake spreader.

To control the laying of the filler strand whereby a plurality of courses thereof are laid over one stake and under another to produce the before mentioned design, character or configuration desired, I provide means associated with the star wheel 37 to actuate the same independent of its associated gear 42 so that in the rotation of the stake holding plates 18 and 24 the same stake is projected from its normal plane a plurality of times in succession and thus a number of filler strand courses are laid upon the same side of said stake instead of laying the strand first upon one side and then upon the other as is carried out in weaving plain fabric portions.

The pattern control mechanism includes an upright threaded shaft 56 journaled at its bottom end in the standard part 6. The top end of said shaft is journaled in a bearing plate 57 supported by posts 58 rising from the top of said standard part. Between the shaft 56 and said posts 58 is provided a squared shaft 59 which is rotatively journaled at its ends in said standard part and said bearing plate 57. On the bottom end of the threaded shaft 56 is fixed a gear pinion 60 arranged in the plane of the bottom flange on the cylinder 15 and adapted to be engaged and driven by the rack 16 thereon. The rack and pinion are so formed that for each rotation of the cylinder, the gear pinion 60 and shaft 56 receive a similar rotation. Associated with said threaded and square shafts 56 and 59, respectively, is a block 61 best shown in perspective in Fig. 9. In said block are formed openings 62 and 63 for the passage of said shafts. In the opening 63 is provided a bearing 64 through which the squared shaft may slide, said bearing also permitting of a rocking movement of said shaft with respect to said block. A disc 64^a suitably fixed to the bottom end of said bearing as by screws, so engages the bottom surface of the block 61, that said bearing moves vertically with said block, said disc and screws being best shown in Fig. 2. The bearing 64 as best shown in

Fig. 4^a includes a dog 65, which extends toward and into close proximity to the cylinder 15. On the top surface of the elevator block 61 is formed an overhanging plate portion 66 which has an opening 67 therein, in line with the opening 62, the threaded shaft 56 also extending through the opening 67. A horizontal pin 68 is carried by said plate portion 66 to one side of the openings 62 and 67 and slidably guided on said pin between said block 62 and said plate portion is a traveller or clutch block 69. Said traveller, which is best shown in perspective in Fig. 8, has a semi-cylindrical threaded recess 70 opening through one side thereof to be engaged with and disengaged from said threaded shaft 56. The traveller has an opening 71 to receive the pin 68 and on that side of the traveller opposite the recess 70 are formed spaced ears 72 to receive the short arm 73 of lever 74 which is pivoted at a point between its ends to said block 61 as best shown in Fig. 7. The lever 74 is intended for manual operation or setting and when the long arm 75 is swung clockwise the traveller will engage the threaded shaft and in the rotation of said shaft will travel or climb upwardly upon the same. When the long arm 75 of the lever is moved counter clockwise the block 69 is disengaged from the shaft and is free from the influence thereof. In the upward or climbing movement of the traveller, the block 61 will, of course, move with it due to the connection between the two. In the vertical movement of the block 61 the bearing 64 and dog 65 will, of course, move vertically therewith because of the construction before described. When said traveller and block have reached their highest elevated position, the long arm 75 will engage a stop member 76 adjustably fixed on the posts 58 and the said stop member is so formed that it will swing said lever counter clockwise and will withdraw the traveller 69 from its engagement with the threaded shaft and will then permit the block 61 to descend by gravity to its lowermost position on the shafts 56-59 which, of course, is adjacent the gear pinion 60.

To the top end of the square shaft 59, just below the plate 57 is clamped an arm 77 which is connected by a spring 78 with the plate 57 in such a manner as to normally urge the dog 65 of the bearing block 64 slideable on said square shaft, toward the cylinder 15. A link 79 having a pin and slot connection at one end with the arm 77 is pivotally connected at its other end to a shorter arm 80 loosely mounted on the top end of the shaft 38. A ratchet wheel 81 is rotatively mounted on the shaft 38 just below said arm, and said ratchet wheel engages with and is fixed to the star wheel 37 so as to rotate therewith as by means of the screw

82 shown in Fig. 4. The arm 80 carries a pawl 83 which is normally engaged with the ratchet in any suitable manner. When the square shaft 59 is rocked as will later appear, a step by step movement is imparted to the ratchet and star wheel 81 and 37, respectively, through the mechanism before described, and this independent of the movement imparted to the star wheel by the gear 42. When such independent movement is imparted to the ratchet and star wheel, the ratchet teeth 41 on the bottom of the star wheel will slip over and depress the pawl 43 and thus pass the same, the said star wheel and gear being again immediately connected by said pawl 43. In this independent movement of the star wheel, the plunger 31 is actuated as before to flex or project outwardly the desired stake so that the spreader 44 may pass the same.

The rocking movement of the squared shaft is controlled by an associated pattern plate 85 carried on a rotatable part of the machine which pattern plate is best shown in perspective in Fig. 6. There is one of these pattern plates for each set of stake manipulating mechanisms and said plates are fixed one above the other on the cylinder 15, as shown in Fig. 1. These plates may be fixed to the cylinder 15 either by welding or by means of screws. I mount said plates in this manner so that they will each actuate its associated mechanism in timed relation and I mount one of the star wheel advancing mechanisms higher on the machine than the other so one plate actuates one mechanism and the other plate actuates the other mechanism. It is apparent that this is the most efficient manner of mounting the pattern plates because if they are both mounted in the same plane, each stake manipulating mechanism would be actuated twice in each rotation of the stake holding rings.

Each pattern plate has a plurality of lugs thereon with oppositely inclined surfaces and said lugs are disposed on said plate in the manner of the outline of the design to be produced in the finished fabric which as shown herein in Fig. 11 is in the shape of a diamond.

In the operation of the machine, after a band of plain fabric has been produced by the over and under interweaving or laying of the filler strand and when said band has approached a sufficient height, the operator actuates the levers 74 to throw the traveller blocks 69 of both stake manipulating mechanisms into engagement with the associated threaded shafts 56. As the rack 16' on the cylinder approaches and meshes with the pinions on the threaded shaft the said pinion will be rotated one complete revolution. With each rotation of said cylinder 15 and pinion 60 the block 61 and parts thereon will climb or travel upwardly a dis-

tance equal to the pitch of the threaded shaft 56. The ratio of the width of the lug on cam plate to the pitch on the threaded shaft 56, will be equal to the number of strands 5 desired to be laid on same side of stakes in pattern. As said block climbs said shaft, it will bring the dog 65 into the plane of the bottommost lugs 86 on pattern, or cam plate, and in the rotation thereof with the cylinder 10 15 said dog will drag over the same and impart a short rocking movement to the square shaft. This rocking movement of the square shaft will cause the star wheel 37 to advance one cog on ratchet 41 or in step with 15 star wheel on other side of machine, thus laying strands on same side of stakes as other side until said dog 65 drags over next bottommost lug on cam plate. This will cause square shaft to rock and advance star 20 wheel 40 one cog or out of step with other side, or back to ordinary weaving again. Ordinarily in the weaving of a plain fabric when a particular stake reaches one projecting mechanism on one side of the machine, it 25 is projected outwardly so that the filler strand is laid on the inside thereof and when said stake reaches the projecting mechanism on the opposite side of the machine, it is not operated upon so as to be projected but it 30 is left so that the filler strand is laid on the other or outside thereof. However, the lugs 35 86 are so disposed that in successive rotations of the cylinder the same stake is projected out of its normal plane a number of times in succession so that a plurality of courses of filler strands are laid over one stake and under the next to produce the design as shown in Fig. 11.

When the block 61 has been moved upwardly on or has climbed the associated threaded shaft a distance greater than the vertical height of the pattern plate, the long arm 75 of the lever 74 will engage the stop cam member 76 on the posts 58 and is caused 40 45 to move counter clockwise. This withdraws the traveller block from engagement with its associated shaft and the block 61 and parts thereon will descend or move downwardly under the action of gravity and the star wheel 37 will then again function to project only every other stake, thus producing plain woven fabric.

Filler strand packing mechanism.

55 The filler strand must of course be packed to produce a fabric suitable for use upon high class articles. In this instance I employ a packing wheel 90 set at an angle to the vertical axis of the machine and mounted 60 for rotation on a suitable shaft 91 carried in a bracket 92 secured to a part of the machine frame. The wheel 90 has a plurality of teeth 93 which mesh with and are driven by the pins 22 on the ring 18 and which causes 65 rotation of said wheel. As said wheel is

thus rotated and being disposed at an angle as before described, the teeth move from a higher plane when first engaging said pins 22 to a lower plane when leaving said pins, the teeth of said wheel passing through the 70 spaces between the stakes to engage said pins. Thus, as the filler strand is brought to the point of insertion over the wheel, the successive incoming portions of the filler strand are progressively moved from their inclined 75 position relative to the preformed fabric to a position parallel to and closely contiguous with the previously inserted filler strands. The packer wheel is so mounted as to be universally adjustable but as the specific 80 manner of adjusting said packing wheel forms no particular part of the present invention it will not be described in detail herein.

As the machine as illustrated and described herein is of a duplex nature, that is as it includes two sets of stake manipulating means, it also includes a stake spreader 44 for each mechanism. As a filler strand is associated with each spreader there is of course two filler strands laid between the stakes at opposite sides of the machine. To this end each filler strand is fed from a supply reel (not shown) and passes therefrom to suitable tension means 95 as best shown in Fig. 1 and then about suitable guide pulleys 96 and up through the stands 45 to the spreaders 44 from which they issue to be laid and packed upon the stakes, as before described.

General operation of machine.

Having thus described in detail the various structures and mechanisms and their cooperative relation, I will briefly state the 105 operation of a completely woven fabric. Assume that the ring 24 is located closely adjacent the ring 18 and that the stakes have been positioned therein, as before described. The filler strand associated with each stake 110 manipulating mechanism may be threaded by hand over and under several of the stakes from the point of exit thereof from the associated spreader. Another manner of starting is to pull a sufficient length of strand from the supply reel and in the rotation of the stake rings the strands will be automatically laid and packed in proper position. In the rotation of said stake rings, the 115 plungers 31 are reciprocated by the star wheels in timed relation to project each alternate stake from its normal plane and as said rotation is continued an upward movement is imparted to the top ring 24 by reason of its engagement with the threaded rod 14. In this manner the fabric is moved upwardly as it is formed. At the proper time the operator actuates the levers 74 to bring the clutch blocks 69 into engagement with the 120 shafts 56 which receives one complete rotation.

tion for every rotation of the fabric and stake rings. In the rotation of said shafts and when the traveller blocks are engaged therewith, a step by step upward movement 5 is imparted to the blocks 61 which brings the dogs into the planes of the lugs 86 on the pattern plates. A rocking movement is thus imparted to the squared shafts 59 and this movement is translated into a step by step 10 movement to the ratchet wheels 81 and to the star wheels 37 independent of the gears 42. This, of course, produces what may be termed "extra" movements of the plungers so that the same stakes are successively 15 moved out of their original plane and a number of courses of strands are laid first on one side and then on the other side of said stakes. After the blocks 61 have passed vertically 20 into planes above the associated pattern plates, the long arms of the levers 74 will engage the stops 76 and will actuate them to disengage the traveller blocks from the threaded shafts when the blocks 61 and parts associated therewith will descend by 25 gravity and will then remain inoperative until again manually actuated. The machine continues its operation in weaving plain fabric wherein the strands are woven individually over one and then under the 30 next stake, as before.

Should it be desired to leave a band in the fabric by passing a plurality of strand courses under one stake and over the next, entirely about the fabric, this may be done 35 by actuating the lever 74 by hand at the predetermined intervals.

When a fabric has been completed the machine is stopped and the incoming filler strands are severed and the fabric then removed 40 from the rings 18 and 24, after which the ring 24 is lowered into proximity with the bottom ring 18 and new stakes inserted, and the machine is again started and operated as before described. Of course, 45 other ways in which the machine may be made ready for weaving will, no doubt, suggest themselves from the above disclosure.

Inasmuch as the disclosure will suggest to others, modified structures whereby the substantial 50 objects of my invention may be attained, I do not wish to be limited to the construction shown and described, except as may be necessary by limitations in the appended claims.

55 I claim as my invention:

1. A machine for weaving a stake and strand fabric embodying therein, means for supporting a plurality of stakes in arcuately spaced relation, mechanism for rotating said 60 stake supporting means, devices actuated in the rotative movement of said means for projecting alternate stakes out of their normal plane, means for laying a filler strand over and under said stakes, and means actuated 65 by said rotative stake supporting means for

successively projecting the same stake out of its normal plane so that a plurality of successive courses of filler strand is laid on the same side of said stake.

2. A machine for weaving a stake and strand fabric embodying therein, means for supporting a plurality of stakes in arcuately spaced relation, mechanism for rotating said stake supporting means, devices actuated in the rotative movement of said means for projecting alternate stakes out of their normal plane, means for laying a filler strand over and under said stakes, normally inactive means adapted to be actuated during the rotation of said stake supporting means to successively project the same stake out of its normal plane so that a plurality of courses of filler strand may be laid on the same side of said stake, and means for operatively connecting said normally inactive means with said rotative stake supporting means to render the same active.

3. A machine for weaving a stake and strand fabric embodying therein, means for supporting a plurality of stakes in arcuately spaced relation, mechanism for rotating said stake supporting means, devices actuated in the rotative movement of said means for projecting alternate stakes out of their normal plane, means for laying a filler strand over and under said stakes, normally inactive means adapted to be actuated during the rotation of said stake supporting means to successively project the same stake out of its normal plane so that a plurality of courses of filler strand may be laid on the same side of said stake, means for operatively connecting said normally inactive means with said rotative stake supporting means to render the same active, and devices automatically operated when a predetermined amount of fabric has been made for rendering said normally inactive means, again inactive.

4. A machine for weaving a stake and strand fabric embodying therein, means for supporting a plurality of stakes in arcuately spaced relation, mechanism for rotating said stake supporting means, devices actuated in the rotative movement of said means for projecting alternate stakes out of their normal plane, means for laying a filler strand over and under said stakes, and means rotative with said stake supporting means and capable of actuating said stake projecting devices for successively projecting the same stake out of its normal plane so that a plurality of successive courses of filler strands is laid on the same side of said stake.

5. A machine for weaving a stake and strand fabric embodying therein, means for supporting a plurality of stakes in arcuately spaced relation, mechanism for rotating said stake supporting means, devices actuated in the rotative movement of said means for

- projecting alternate stakes out of their normal plane, means for laying a filler strand over and under said stakes, and pattern plates rotative with said stake supporting means for controlling said stake projecting devices which will act to project the same stake out of its normal plane so that a plurality of successive courses of filler strands is laid on the same side of said stake.
6. A machine for weaving a stake and strand fabric embodying therein, means for supporting a plurality of stakes in arcuately spaced relation, mechanism for rotating said stake supporting means, devices actuated in the rotative movement of said means for projecting alternate stakes out of their normal plane, means for laying a filler strand over and under said stakes, and pattern plates rotative with said stake supporting means and including means arranged in the form of the design to be produced, said last mentioned means being capable of actuating said stake projecting devices to project the same stake out of its normal plane so that a plurality of successive courses of filler strands is laid on the same side of said stake and on the other side of adjacent stakes in accordance with the arrangements of said means on the pattern plate.
7. A machine for weaving a stake and strand fabric embodying therein, stake supporting rings one vertically movable with respect to the other, mechanism for rotating said stake supporting rings, members on said rings for holding stakes in the desired spaced relation, devices actuated in the rotative movement of said rings for projecting alternate stakes out of their normal plane, means for laying a filler strand over and under said stakes, and means capable of operation after a predetermined amount of relative vertical movement of said rings for causing said stake projecting devices to successively project the same stake out of its normal plane so that a plurality of successive courses of filler strands is laid on the same side of said stake.
8. A machine for weaving a stake and strand fabric embodying therein, rotative stake supporting rings one being vertically movable with respect to the other, means on said rings for holding stakes in the desired spaced relation, devices actuated in the rotative movement of said rings for projecting alternate stakes out of their normal plane, means for laying a filler strand over and under said stakes, means associated with said stake projecting devices for actuating them to successively project the same stake out of its normal plane so that a plurality of successive courses may be laid on the same side of said stake, and means rotative with one of said rings and controlling the operation of said last mentioned means

at relatively different vertical spacings between said rings.

9. A machine for weaving a stake and strand fabric embodying therein, a standard, means rotative on said standard and including stake holding means, devices on said standard for projecting alternate stakes out of their normal plane, means for laying a filler strand over one stake and under adjacent stakes, means on said standard and driven from said rotative means for actuating said stake projecting devices, and means associated with said last mentioned means and capable of being actuated by a part of said rotation means for controlling the operation of said projecting devices whereby said devices will act to successively project the same stake out of its normal plane so that a plurality of successive courses of filler strands are laid upon the same side of said stake.

10. A machine for weaving a stake and strand fabric embodying therein, a standard, means rotative on said standard and including stake holding means, devices on said standard for projecting alternate stakes out of their normal plane, means for laying a filler strand over one stake and under adjacent stakes, means on said standard and driven from said rotative means for actuating said stake projecting devices, and a pattern plate rotative on the standard for controlling the operation of said means associated with said stake projecting devices whereby said devices will act to successively project the same stake out of its normal plane so that a plurality of successive courses of filler strands are laid upon the same side of said stake.

11. A machine for weaving a stake and strand fabric embodying therein rotative stake holding means, reciprocating devices for projecting alternate stakes out of their normal plane, a member rotative with said stake holding means, means actuated by said rotative member for imparting a reciprocating movement to said devices, and normally inactive means associated with said last mentioned means and also operated by said rotative member to cause said reciprocating devices to successively project the same stake outwardly so that said filler strand is laid in successive courses on the same side of said stake and on the other side of adjacent stakes.

12. A machine for weaving a stake and strand fabric embodying therein rotative stake holding means, reciprocating devices for projecting alternate stakes out of their normal plane, a member rotative with said stake holding means, means actuated by said rotative member for imparting a reciprocating movement to said devices, a pattern plate carried by said rotative member, and normally inactive means associated with said

last mentioned means and actuated by the said pattern plate to cause said reciprocating device to successively project the same stake outwardly so that said filler strand is laid in successive courses on the same side of said stake and on the other side of adjacent stakes.

13. A weaving machine embodying therein, rotative means for supporting stakes in arcuate spaced relation, a reciprocating device for projecting alternate stakes out of their normal plane a rotative member driven in timed relation with said rotative means, and means interposed between said member and reciprocating device for transposing the rotary movement of said member into reciprocating movement of said device.

14. A weaving machine embodying therein, rotative means for supporting stakes in arcuate spaced relation, a reciprocating device for projecting alternate stakes out of their normal plane, a rotative member driven in timed relation with said rotative means, a toothed wheel adapted to be driven by said member, and means interposed between said toothed wheel and said reciprocating device for imparting reciprocating movement to said device.

15. A weaving machine embodying therein, rotative means for supporting stakes in arcuate spaced relation, a reciprocating device for projecting alternate stakes out of their normal plane, a rotative member driven in timed relation with said rotative means, means normally driven by said member and including parts for imparting a reciprocating movement to said device, and means associated with said last mentioned means and capable of actuating the same independent of said rotative member.

16. A weaving machine embodying therein, rotative means for supporting stakes in arcuate spaced relation, a reciprocating device for projecting alternate stakes out of their normal plane, a rotative member driven in timed relation with said rotative means, a toothed wheel arranged adjacent said rotative member a clutch device between said wheel and rotative member, and means for translating the rotative movement of said wheel into reciprocating movement of said device.

17. A weaving machine embodying therein, rotative means for supporting stakes in arcuate spaced relation, a reciprocating device for projecting alternate stakes out of their normal plane, a member rotative with said stake supporting means, a gear driven by said rotative member, a toothed member normally rotative with said gear but capable of being advanced rotatively with respect to said gear, and means interposed between said toothed member and reciprocating device for imparting movement to said reciprocating device.

18. A weaving machine embodying therein, rotative means for supporting stakes in arcuate spaced relation, a reciprocating device for projecting alternate stakes out of their normal plane, a member rotative with said stake supporting means, a gear driven by said rotative member, a toothed member normally rotative with said gear but capable of being advanced rotatively with respect to said gear, means for advancing said toothed member with respect to the gear, and means interposed between said toothed member and reciprocating device for imparting movement to said reciprocating device.

19. A weaving machine embodying therein, rotative means for supporting stakes in arcuate spaced relation, a reciprocating device for projecting alternate stakes out of their normal plane a member rotative with said stake supporting means, a gear driven by said rotative member, a toothed member normally rotative with said gear but capable of being advanced rotatively with respect to said gear, a ratchet wheel associated with said toothed member for advancing the same with respect to said gear, means between said toothed member and reciprocating device for imparting movement thereto and means for actuating said ratchet wheel.

20. A weaving machine embodying therein, rotative means for supporting stakes in arcuate spaced relation, a reciprocating device for projecting alternate stakes out of their normal plane, a member rotative with said stake supporting means and including lugs arranged thereon in pattern form, a gear driven by said rotative member, a toothed member rotative with said gear and capable of being advanced with respect thereto, means operatively connected to said toothed member to advance it rotatively with respect to said gear, means connecting said reciprocating device with said toothed member and means actuated by said pattern lugs for advancing said toothed member with respect to said gear.

21. A weaving machine including a rotating cylinder having a top gear member, a gear meshing with said top gear member, a toothed member normally driven by said gear but capable of being advanced with respect to the same, a reciprocating device, means connecting said toothed member and device for reciprocating the same, lugs disposed on said cylinder in different vertical planes, a pawl and ratchet mechanism operatively connected to said toothed member to advance it independently of said gear, a rock shaft for actuating said pawl, and means associated with said rock shaft and adapted to engage said lugs on the cylinder for rocking said rock shaft.

22. A weaving machine including a rotating cylinder having a top gear member, a gear meshing with said top gear member,

a toothed member normally driven by said gear but capable of being advanced with respect to the same, a reciprocating device, means connecting said toothed member and device for reciprocating the same, lugs disposed on said cylinder in different vertical planes, a pawl and ratchet mechanism operatively connected to said toothed member to advance it independently of said gear, a 5 rock shaft for actuating said pawl, means associated with said rock shaft and adapted to engage with said lugs on said cylinder to impart movement to said rock shaft, and means intermittently actuated by said 10 cylinder to bring said means associated with said rock shaft in the planes of said lugs on said cylinder.

15

23. A weaving machine including a rotating cylinder having a top gear member, a 20 gear meshing with said top gear member, a toothed member normally driven by said gear but capable of being advanced with respect to the same, a reciprocating device, means connecting said toothed member and device for reciprocating the same, lugs disposed on said cylinder in different vertical 25 planes, a pawl and ratchet mechanism operatively connected to said toothed member to advance it independently of said gear, a rock shaft for actuating said pawl, means 30 associated with said rock shaft and adapted to engage with said lugs on said cylinder to impart movement to said rock shaft, a screw threaded shaft intermittently driven from 35 said cylinder, and a device adapted to be engaged with said threaded shaft for moving said rock shaft actuating means into the plane of said lugs.

24. A weaving machine including a rotating cylinder having a top gear member, a 40 gear meshing with said top gear member, a toothed member normally driven by said gear but capable of being advanced with respect to the same, a reciprocating device, 45 means connecting said toothed member and device for reciprocating the same, lugs dis-

posed on said cylinder in different vertical planes, a pawl and ratchet mechanism operatively connected to said toothed member to advance it independently of said gear, a 50 rock shaft for actuating said pawl, means associated with said rock shaft and adapted to engage with said lugs on said cylinder to impart movement to said rock shaft, a screw threaded shaft intermittently driven 55 from said cylinder, a traveller normally disengaged with said threaded shaft and with which said rock shaft operating means is movable, and means for connecting said traveller to said threaded shaft so that said 60 rock shaft operating means is brought into the planes of said lugs on said cylinder.

25. A weaving machine including a rotating cylinder having a top gear member, a 65 gear meshing with said top gear member, a toothed member normally driven by said gear but capable of being advanced with respect to the same, a reciprocating device, means connecting said toothed member and device for reciprocating the same, lugs disposed on said cylinder in different vertical 70 planes, a pawl and ratchet mechanism operatively connected to said toothed member to advance it independently of said gear, a rock shaft for actuating said pawl, means 75 associated with said rock shaft and adapted to engage with said lugs on said cylinder to impart movement to said rock shaft, a screw threaded shaft intermittently driven from said cylinder, a traveller normally disengaged with said threaded shaft and with 80 which said rock shaft operating means is movable, means for connecting said traveller to said threaded shaft so that said rock shaft operating means is brought into the 85 planes of said lugs on said cylinder, and automatic means for tripping said traveller from the threaded shaft at a predetermined time.

In testimony whereof, I have hereunto set 90 my hand, this 5th day of August, 1925.

MARSHALL B. LLOYD.
